(57) **CLAIM**

The ornamental design for a noise cancellation device for use with recording devices, as shown and described.

DESCRIPTION

FIG. 1 is a perspective view of a noise cancellation device for use with recording devices showing our new design; FIG. 2 is a left elevational view thereof; FIG. 3 is a right elevational view thereof; FIG. 4 is a front elevational view thereof; FIG. 5 is a rear elevational view thereof; FIG. 6 is a top plan view thereof; and, FIG. 7 is a bottom plan view thereof. The broken line showing in FIGS. 1–7 is for illustrative purposes only and forms no part of the claimed invention.
